UNITED STATES PATENT OFFICE.

JAMES NIXON KENNY, OF OTTAWA, ONTARIO, CANADA.

CONVEYER BELT.

1,422,208.

Specification of Letters Patent. Patented July 11, 1922.

Application filed January 13, 1921. Serial No. 436,932.

To all whom it may concern:

Be it known that JAMES NIXON KENNY, a subject of the King of Great Britain, residing at the city of Ottawa, in the Province 5 of Ontario and Dominion of Canada, has invented certain new and useful Improvements in Conveyer Belts, of which the following is a specification.

This invention relates to improvements in 10 conveyer belts and particularly to such belts as are used in the type of conveyer employed in cloth or wool drying machines in which it is necessary to provide sections of a character to convey the cloth or wool and yet 15 permit of the passage of drying air therethrough, and the objects of the invention are to provide a simple and effective and strong frame or section for conveyers of this type which will give adequate support to the 20 cloth or wool, will be durable and which will avoid the production of unnecessary friction in use, also the unnecessary expense of screen repairs. Further objects are to generally improve and simplify the construction of the device and to better adapt 25 it to perform the functions required of it, and it consists essentially of the improved construction hereinafter described in detail in the accompanying specification and drawings.

In the drawings:—

Figure 1 is a perspective view of an embodiment of the invention.

Figure 2 is a sectional detail on the line 35 $x-x$, Figure 1.

Figure 3 is a sectional detail on the line $y-y$, Figure 1.

Figure 4 is a sectional detail on the line $z-z$, Figure 2.

Figure 5 is a sectional detail on the line $t-t$, Figure 2.

Figure 6 is a sectional detail of the tubular side of the frame of the section.

In the drawings, like characters of reference indicate corresponding parts in all the figures.

Referring to the drawings:—

A represents one of the sections of the conveyer including a frame formed by tubular side members 10 and 11 and end members 12 and 13; each of the end members 12 and 13 are constituted by parallel bars 14 and 15 which are connected to the tubular side member 10 by means of pivot pins 16, 55 the said pivot pins also serving to connect the end members 14 and 15 on adjacent sec-

tions whereby all the sections are linked together in a continuous flexible conveyer. The members 14 and 15 are maintained in their spaced relation by means of a spacing 60 roller 17 surrounding the pin 16 and extending between the perforated ends of the members 14 and 15, through which the pin 16 extends. Binding of the end members against the end of the tubular members is 65 prevented by a washer 18 surrounding the pin 16 and abutting the end of the tubular member 10 or 11 held in position by means of a cotter pin 19 which extends between it and the end of the members 15, as shown in 70 Figure 4. It will be observed also from this figure that the pin 16 extends at a distance into the end of the tubular member whereby it may be maintained in position by friction.

The centre of the section A is filled by a foraminous supporting member 20 conveniently constructed of wire mesh which at one side is inserted through a longitudinally extending slot 21 formed in the member 10, as illustrated in Figure 3, the foraminous supporting member being retained in such position by a metal clip 22 surrounding the member 10 and being riveted or otherwise secured to the foraminous supporting 85 member. The ends and opposite sides of the foraminous member adapted to be inserted through the slot 21 are re-inforced by binding material such as tin or galvanized iron which extends around the edges forming an 90 inner frame 23. The foraminous supporting member is also retained in its position at substantially the centre of the tubular members 10 and 11 by means of clips 24 secured to the end members 15 and engaging the 95 ends of the inner frame 23 of the foraminous supporting member. Additional support is also given by a clip 25 on the foraminous member extending around and fitting closely to the tubular member 11, to 100 avoid sagging of screens in centre when going over hexagon sprockets.

To give additional support to the edges of the foraminous supporting member, the material forming the inner frame 23 is extended into the interior of the tubular member 10 and forms partially cylindrical projections 26 and 27 which embrace the pins 16 as shown in Figures 2 and 4.

It will be found from the foregoing that 110 the various parts referred to will constitute a conveyer section well adapted to support

the cloth or wool in a dryer machine and adapted to resist wear and at the same time remain in its proper position and operate with a minimum amount of friction, also a saving of a number of screen sections, and allowing of equal heating space.

As many changes could be made in the above construction and many widely different embodiments of my invention within 10 the scope of the claims constructed without departing from the spirit or scope thereof, it is intended that all matter contained in the accompanying specification and drawings shall be interpreted as illustrative and 15 not in a limiting sense.

What I claim as my invention is:—

1. A conveyer section comprising tubular side members, end members connected to the side members, means for pivotally connecting adjacent sections, one of the side members having a longitudinal slot therein and a supporting member located in the centre of the section extending into the slot in the side member, and a clip on the said supporting member extending over the opposite side member to that having a slot therein.

2. A conveyer section for the purposes specified comprising tubular side members, an end member, one of the side members 30 having a longitudinal slot therein, a supporting member extending in the slot and clips on the end members supporting the ends of the supporting member.

3. In a conveyer section, a tubular side member having a slot therein, a foraminous supporting section, an inner frame extending around the edges thereof having metallic projections thereon extending through the slot in the said member.

4. In a conveyer section, a tubular side member having a slot therein, a foraminous supporting section, an inner frame extending around the edges thereof having metallic projections thereon extending through the slot in the said member and a pivot pin entering the side section and engaging the said projections.

5. A conveyer section comprising tubular side members, end sections including space members and pivot pins extending through the said end sections into the tubular members, a foraminous supporting section located between the tubular side members and the end sections, spacing rollers on the pivot pins between the members of the end sections and washers on the pivot pins adapted to abut the ends of the tubular members and means for holding the washers in position.

In witness whereof I have hereunto set 60 my hand in the presence of two witnesses.

JAMES NIXON KENNY.
